UNITED STATES PATENT OFFICE.

THOMAS BERRY LOCKLEY, OF GOULBURN, NEW SOUTH WALES, AUSTRALIA.

AUXILIARY FUEL-BOX FOR STOVES, &c.

No. 869,581.

Specification of Letters Patent.

Patented Oct. 29, 1907.

Application filed September 11, 1906. Serial No. 334,133.

To all whom it may concern:

Be it known that I, THOMAS BERRY LOCKLEY, of Ma-
berry Clinton street, Goulburn, in the State of New
South Wales and Commonwealth of Australia, teacher
5 of carpentry, have invented a new and useful Improved
Auxiliary Fuel-Box for Stoves, &c., of which the follow-
ing is a specification.

This invention of improved auxiliary fuel box for
stoves and the like has been specially devised in order
10 to allow the use of wood fuel in lengths longer than the
ordinary firebox will allow. And this invention is ap-
plicable to washing boiler, steamboiler and other sur-
faces.

According to this invention an improved auxiliary
15 fuel box for stoves and the like consists of a box open
at one end and having a removable lid and is generally
oblong and rectangular but should conform to the shape
of the firebox of a stove and is supported in front of and
with its floor or bottom level with said firebox by a
20 bracket from a U-shaped frame the return of which
rests upon the hearth or floor or projecting foot plate of
stoves whose fronts are not in the one vertical plane and
the ends whereof take under the hollow nosing of the
stove plate. In some cases the box may be constructed
25 in two parts telescoping one within the other. But in
order to illustrate the carrying into practical effect of
this invention the same will now be described with
reference to the drawings accompanying and forming
part of this complete specification in which

30 Figure 1 is a perspective view of an ordinary stove
with improved auxiliary fuel box attached thereto and
Fig. 2 a cross section on plane 2—2 in Fig. 1 but showing
a telescopic auxiliary fuel box. Fig. 3 is a sectional de-
tail view showing the hinged flap for closing the inner
35 end of the auxiliary fuel box.

The box 3 preferably of sheet iron has a strengthening
band of iron 4 riveted around its inner edge at the open
end 5 and a removable lid or cover 6 and a riding piece
7 on each side adapted to rest upon the top bar of the
40 side brackets having horizontal member 8 and diagonal
9 extending outwardly on either side from the U-shaped
frame. The return of this U-frame rests upon the floor
while the ends of legs 10 take under the hollow nose 11
of the stove plate retaining the whole in position. On
45 the side of said box 3 is a stop 12 adapted to strike
against the diagonal bar 9 of the bracket 8 so as to limit
outward sliding of the box 3 and its withdrawal from the
fire box. As shown in Fig. 2 the fuel box 3 may be
made in two parts telescoping one in the other the outer
50 part 3 being supported as described by the member 9

and in this case the box 3 has in each side a stop pin 15
which by means of the slot 16 allows the inner part 13
of the box to slide in and out. A casing 17 protects this
pin and slot so that draft may not pass through when the
box is extended.

55

In use the front bars or grate are let down or removed
and the legs 10 of the frame carrying the brackets 8 and
9 are placed under the nose 11 of the stove-plate and
said frame pushed in against the stove. The box 3 carrying
10 the riding pieces 7 is placed upon the members 8 60
with the riding pieces 7 taking thereon. The lid is re-
moved as required and lengthy pieces of wood fuel
placed in the box 3 and these pushed along into the fire-
box of the stove from time to time the lid being returned
65 to place. When it is necessary the box 3 is drawn out
to increase the available space but normally is pushed
in tight against the stove.

If desired a hinged flap 18 internally of the box may
be arranged to fall against the inner strengthening band
70 of iron 4 or to be drawn up clear to the top of the box
and controlled by chain or handle 19 through hole in
top and having a large ring or link 20 at its end to fasten
on to handle if it were found necessary to fasten it while
the box was filled with large log. This hinged flap will
75 prevent heat escaping into the fuel box when the fuel
has burned short and so reducing liability to burning of
person or scorching of clothes.

Having now fully described and ascertained my said
invention and the manner in which it is to be performed
I declare that what I claim is—

80

1. An attachment for stoves and the like, comprising an
auxiliary fuel box and a U shaped support, the ends of
which are adapted to engage the top plate of the stove, and
a bracket carried by said support and having a slide for
the auxiliary fuel box.

85

2. An attachment for stoves and the like, comprising an
auxiliary fuel box having an open end adapted to com-
municate with the fire box of the stove, supporting means
adapted to be applied to the exterior of the stove, and a
bracket applied to said means and having a horizontal
slide for the auxiliary fuel box.

90

3. An attachment for stoves and the like, comprising an
auxiliary fuel box having an open end adapted to com-
municate with the fire box of the stove, means for support-
ing said auxiliary fuel box comprising a horizontal slide, a
pin and slot connection between said fuel box and slide,
and a casing 17 within said fuel box for protecting the
slot openings thereof.

95

In testimony whereof I have signed my name to this
specification in the presence of two subscribing witnesses. 100

THOMAS BERRY LOCKLEY.
